UNITED STATES PATENT OFFICE.

SIGMUND FREY, OF LOS ANGELES, CALIFORNIA.

CANTEEN SET.

Application filed February 6, 1926. Serial No. 86,436.

This invention relates to canteen sets of the type used, for example, as accessories on automobiles to hold supplies of water, oil and gasoline.

5 An object of the invention is to provide a set of this type that is relatively inexpensive to manufacture and that is neat in appearance.

Another important object is to effect 10 clamping of the canteens in a manner to prevent them from rattling.

A further object is to make provision for 15 securely holding the canteens and at the same time provide for quick release thereof so that the canteens can be quickly detached from the holder for discharging the contents of said canteens.

Other objects and advantages will appear in the subjoined detailed description.

20 The accompanying drawings illustrate several embodiments of the invention:

Figure 1 is a plan view of a canteen set constructed in accordance with the provisions of this invention, the holder being 25 shown closed and latched.

Figure 2 is a front elevation of Fig. 1.

Figure 3 is an end elevation of Fig. 1, a portion of the holder being shown in section.

30 Figure 4 is an enlarged broken sectional elevation on the line indicated by 4—4, Fig. 2.

Figure 5 is an end elevation of a modified form of canteen set constructed in accordance with the provisions of this invention.

Figure 6 is an end elevation of another modified form of canteen set constructed in accordance with the provisions of this invention.

40 Figure 7 is a fragmental perspective view of the upper portion of the canteen set shown in Fig. 6, the releasable means for contracting the holder being shown in open position.

First referring to the form of the invention illustrated in Figs. 1 to 4, inclusive, of the drawings, there is provided a holder comprising, in this instance, a split band 11 that encircles a canteen or canteens 12 positioned end to end within the band. In Figs. 1 and

50 2, three canteens are shown but this number may be less or greater, as desired. The band is preferably constructed of sheet metal and is more or less flexible and resilient.

Means are provided projecting inwardly 55 from the band to prevent endwise movement of the canteens in the band, when the band

is contracted on the canteens, and these means may be variously constructed and, in this instance, are as follows: The side edges of the band are provided with inwardly projecting flanges 13 adapted, when the band is contracted, to extend over the outer ends of the endmost canteens. The depth of this flange may be comparatively slight and it also serves to strengthen the band to prevent 60 undue distortion thereof. The canteens, in this instance, are circular as is the band.

Another object is to provide the band with supports 14 which are in the nature of feet, and these feet may be secured to the 70 running board of an automobile by screws, not shown, passing through holes 15 in the supports 14. Registering with the supports 14 are openings 16 in the band to accommodate feet 17 projecting from the peripheries 75 of the canteens. The feet 14, in this instance, have recesses 18 into which the canteen feet 17 project. The feet 14 may be of integral construction with the band or, if desired, may be separately constructed and welded 80 or otherwise secured to the band.

A releasable means is provided for connecting the ends of the band 11 for the purpose of clamping said ends and holding the band contracted upon the canteens and this 85 means may be of any suitable construction and, in this instance, is as follows: The opposite ends of the band form circular members or ears 19, 20 which nest or seat within semi-circular members 21, 22 at the longitudinal margins of a latching member 23 which may be constructed of sheet metal. The members 20, 22 constitute a hinge for hingedly connecting the member 23 to the band. The member 23 covers and protects 90 the canteen spouts 36. It will be noted that the semi-circular members 21, 22 underlie or hook beneath the members 19, 20. Thus, it will be seen that when the latching member 23 is snapped closed it cannot spring open, 100 and that the latching member is thus held in proper position for clamping by such means as will be described hereinafter.

In order to contract the member 23 so as to in turn contract still further the band 105 upon the canteens, I provide a pin or pins 24 having heads 25 which engage the outer face of the member 22 and extend through holes 26 formed in said member. The pins 24 pass through slots 27 in the members 20 and through slots 28 in the members 19, and said pins also pass through holes 29 in the 110

members 21 and project beyond the outer face of the members 21. The projecting ends of the pins are threaded at 30 to receive wing nuts 31 which may be tightened 5 against the member 23 so as to draw the members 19, 22 toward each other. It will then be necessary, in order to unhook the member 23 from the band, to loosen the wing nuts 31, whereupon the portion 21 of the 10 member 23 may be sprung sufficiently, by forcing the pins 24 upwardly, to release the member 21 from the member 19. The contact means provided by the pins 24, it will be observed from Figure 4, are mounted in 15 an off-center position so that when the wing nuts 31 are screw-threaded onto the pins 24 to draw the ends of the band 11 into contact with the canteens, the pins 24 will tend to rotate to a position to tighten the ends of the 20 band 11 and will not tend to rotate to a position of release. This provision of the off-center position of the pins 24 aids in the insuring of the provision of a holder which will prevent the rattling of the canteens 12. 25 After disengagement of the member 23 from the member 19, the canteens are removed endwise out of the holder past either of the flanges 13, since the band will expand sufficiently to permit of this movement of 30 the canteens.

Now referring to the modification illustrated in Fig. 5, the elements that function the same as those described above are indicated by the same reference characters with 35 the addition of the letter "a." It will be seen that the only difference between this modification and the construction above described is that the band is of sectional construction, the sections being indicated at 32, 33. These 40 sections are movably connected by a hinge shown at 34. This form of the invention operates the same as that shown in Figs. 1 to 4, excepting that the band 11^a expands a little more freely than the band 11, owing to 45 the provision of the hinge 34.

Now referring more particularly to the modification of the invention illustrated in Figs. 6 and 7, the parts that function the same as those described above in connection 50 with Figs. 1 to 5 are indicated by the same reference characters with the addition of the letter "b." This form of the invention dispenses with the equivalent of the member 23, the free ends of the band sections being 55 bent outwardly to form ears 19^b, 20^b and the pins 24^b passing through holes 26^b in the ears 20^b and through slots 28^b in the ears 19^b, said slots opening to the ends of the ears 19^b so that, when it is desired to 60 open the holder the wing nuts 31^b will be

loosened sufficiently to permit of the pins 24^b being thrown upwardly to disengage the slots 28^b, as shown in Fig. 7.

The band 11^b, in this instance, is provided with openings 35 through which the spouts 36^b of the canteens project when the holder is closed. To release the canteens, the pins 24^b being shown in open position as in Fig. 7, the section 32^b will be swung open on its hinge 34^b, thus disengaging the spouts 36^b and permitting any one of the canteens to be withdrawn from the section 33^b.

I claim:

1. A canteen set comprising a split band, means to secure the middle portion of the band to a support, a canteen seated in the band, a latching member hinged to one end of the band and constructed to releasably hook onto the other end of said band. 75

2. A canteen set comprising a split band, supports formed on the bottom of said band and provided with recesses, a canteen within the band having feet projecting into the recesses, and releasable means to contract the band on the canteen. 80

3. A canteen set comprising a split band, a canteen within the band having a spout on its periphery, and a member movably connected with one end of said band and releasably connected with the other end of said band and covering and protecting said spout. 85

4. A canteen set comprising a split band, a canteen within the band having a spout on its periphery, releasable means connected with the ends of the band for contacting the band on the canteen, and a member connected with the ends of the said band and with the said releasable means for covering and protecting the said spout. 95

5. A canteen set comprising a circular band provided with feet to rest upon a support to prevent turning of said band on the support, the band having a split at a point approximately opposite to the feet, a canteen within the band, and a means to contract the band upon the canteen. 100

6. A canteen set comprising a circular band provided with feet to rest upon a support to prevent turning of said band on the support, the band having a split at a point approximately opposite to the feet, a canteen within the band, and a means to contract the band upon the canteen, the band provided with inwardly projecting flanges adapted to extend partly over the ends of the canteen. 110

Signed at Los Angeles, Calif., this 22 day of January, 1926.

SIGMUND FREY.
